United States Patent Office

Des. 220,472
Patented Apr. 20, 1971

220,472

BUILDING

Cesar Pelli, Los Angeles, Calif., assignor to American
Snacks, Inc., Chelsea, Mass.

Filed Sept. 17, 1969, Ser. No. 19,179

Term of patent 14 years

Int. Cl. D25—04

U.S. Cl. D13—1

FIG. 1

FIG. 2

Des. 220,472

PAGE 2

FIG. 3

FIG. 4

FIG. 5

FIG. 1 is a perspective view of a building showing my new design;

FIG. 2 is a front view thereof;

FIG. 3 is a left side view thereof;

FIG. 4 is a rear view thereof; and

FIG. 5 is a top view thereof.

The right side view is a mirror image of the left side view as shown in FIG. 3.

I claim:

The ornamental design for a building, as shown and described.
